DESIGN FOR A COAL AND WOOD BURNING HEATER

King E. Ehret, Belleville, Ill., assignor to Oakland
Foundry Company, Belleville, Ill.

Application September 13, 1934, Serial No. 53,275

Term of patent 3½ years

To all whom it may concern:

Be it known that I, King E. Ehret, a citizen of the United States, and a resident of the city of Belleville, county of St. Clair, and State of Illinois, have invented a new, original, and ornamental Design for a Coal and Wood Burning Heater, of which the following is the specification, and reference being had to the accompanying drawing, forming a part thereof:

Figure 1 is a perspective of my heater.
Figure 2 is a front elevation of my heater.
Figure 3 is a side elevation of my heater.
The exposed face of my heater has a surface treatment known as hammered metal.

I claim:

The ornamental design for a coal and wood burning heater, as shown and described.

KING E. EHRET.
